UNITED STATES PATENT OFFICE.

JOHN J. PINK, OF CHICAGO, ILLINOIS.

MAGAZINE FOR MOVING-PICTURE MACHINES.

No. 872,970.

Specification of Letters Patent.

Patented Dec. 3, 1907.

Application filed March 28, 1907, Serial No. 365,150.

To all whom it may concern:

Be it known that I, JOHN J. PINK, a citizen of the United States, residing in the city of Chicago, in the county of Cook and State of Illinois, have invented certain new and useful Improvements in Magazines for Moving-Picture Machines, of which the following is a full, clear, and exact description.

My invention relates to certain new and useful improvements in magazines for moving picture machines, the object of the invention being to provide a simple, substantial and practically fire proof magazine which may be readily attached to or removed from machines of this class.

Another object is to provide an entrance to the magazine proper, through which the reel may be readily inserted or removed, which entrance or opening is uncovered by sliding or telescoping the cover upon the receptacle.

The invention further relates to other novel features of construction a description of which will be found in the following specification and the essential features of which will be more definitely pointed out in the claims appended hereto.

The invention is clearly illustrated in the drawings furnished herewith in which

30 Figure 1 is a side view of a magazine embodying my improvements. Fig. 2 is a view looking at the opposite side of the same. Fig. 3 is an edge view thereof. Fig. 4 is a vertical section taken on the line 4—4 Fig. 3, 35 the reel or spool being removed from the magazine. Fig. 5 is a vertical cross section taken on the line 5—5 Fig. 1. Figs. 6, 7, 8 and 9 are fragmental side views of the side sections of the magazine. Figs. 10 and 11

40 are side views of certain reinforcing washers used in hinging or pivoting the cover upon the receptacle. Fig. 12 is a perspective view of a hollow rivet. Fig. 13 is a fragmental view of the cover looking in the direction of the arrow 13 in Fig. 4. Fig. 14 is a similar view of the receptacle. Fig. 15 is a plan view of a roller and its bracket, and Fig. 16 is a similar view of another guide roller and its bracket.

50 In these views 10, represents a base or standard, which is adapted to be bolted or otherwise secured upon the moving picture machine, a fragment of which appears at A. Said standard contains an arm 11, to which 55 the casing or magazine proper is secured. Said arm is formed with a journal bearing

13, at its upper end, in which is journaled a spindle 20, that carries the reel or spool B. A second spindle or shaft 40, is journaled in the lower end of the standard, which spindle 60 carries a grooved pulley 41, and a crank 42, the crank furnishing means for rotating the shaft 40. The spindle 20, carries a grooved pulley 21, which is connected to the pulley 41, by a belt 22, as clearly shown in the drawings, and said spindle is formed with a circumferential groove 23, in which rests a spring latch 24, that is fastened upon the arm 11. Except for the groove and spring latch the spindle is free to be withdrawn 70 from its bearing, and said groove and spring latch furnish means for locking the spindle against longitudinal movement in the bearing. The spindle also bears a key 25, which seats a groove in the hub of the reel. 75

The arm 11, of the base has secured to it, a brace 12, which is provided with radial strengthening arms 13¹, to which one of the walls of the receptacle is riveted. This brace acts as a stiffening member for the 80 wall of the magazine thus avoiding any buckling or warping of said wall.

The magazine proper is shown at 50, and contains two halves 51, 52, the half 51, being secured to the standard and serving as a 85 receptacle, and the half 52, serving as the cover and being hinged or pivoted to the half 51, and telescoping therein. The receptacle 51, is preferably formed of two side plates 53, 54, which are practically semicircular in form, and connected by a back plate 55. The cover 52 is likewise formed of two sides 56—57, approximately semi-circular in form, and connected by a back plate 58. The side plates 56, 54, of the cover and receptacle are each formed with a pivot opening that is concentric with respect to the curved margin or periphery of the plates, and each plate has riveted to itself at its center, a reinforcing metal washer 60. A spacing 100 washer 61 is interposed between the plates 56—54 to prevent the projecting heads of the rivets from striking each other and thereby interfering with the movement of the cover upon the receptacle. The two plates 56—54 105 are pivotally secured together by a rivet 63 which is headed on the outer faces of the washers 60. The side plates 57—53 are also perforated at their axes, the holes however being somewhat larger than the holes for the 110 rivet 63, and said plates 57, 53 are each provided with a reinforcing washer 59. A

spacing washer 59^a is interposed between the two plates 57—53, and a hollow rivet 61^a pivotally connects the plates 57—53 and washers 59—59^a, together. The bearing 13 extends through an opening in the reinforcing brace 12, and through the hollow rivet 61^a, into the magazine, thus providing a long bearing for the spindle 20. A flat spring 31, is secured to the washer 60 on the 10 cover, which spring bears against the reel B and holds it in position upon the spindle.

The lower meeting edges of the back plates 55, 58, are cut away at 55^a, 58^a to receive idle rollers 70, 71, which rollers are 15 journaled in brackets 72, 73 riveted or otherwise secured upon the halves 51, 52, of the magazine. Said rollers guide the ribbon or film in its passage to and from the film spool. A hook 74 is pivoted upon the receptacle 51, and engages with a pin 75, upon the cover 52, to lock the cover down upon the receptacle 51. In operation, the cover is 20 swung into the receptacle 51 to expose the interior, the belt 22, is removed from the pulleys, the spindle 20 released from the spring latch 24, and the spindle withdrawn from the reel or spool B. The reel may then be removed from the magazine and another reel substituted for the one removed. The 25 spindle 20 is then thrust through the hub of the reel, the cover drawn down and locked in place, and the belt placed upon the pulleys. It is understood that in operating the moving picture machines of which the magazines form a part, the ribbon or film is unrolled from the reel B, and drawn through the machine. It may afterwards be rewound upon the reel by turning the crank 42.

In magazines of this class, it is exceedingly important, that the ribbon within the magazine, be protected from fire, as said ribbon is usually composed of highly combustible and inflammable material, and this magazine has been particularly designed 40 with a view of meeting said requirements. It should be noted that when the cover is shut, there are practically no apertures through which fire may communicate with the interior of the magazine. Furthermore, 45 when the magazine is opened to expose the interior no additional space is required for the cover, so that economy of space may be had without complicating the structure. This is particularly advantageous for the 50 reason that these machines are frequently set up in closely confined quarters, which 55 makes it necessary to economize space.

I claim as new and desire to secure by Letters Patent:

60 1. In a magazine for moving picture machines, the combination of a suitably supported cylindrical telescoping casing, a spindle axially disposed with respect thereto, and a pivot connection between the telescoping members independent of the spindle.

2. A magazine for moving picture machines, comprising a suitably supported casing, containing two telescoping and approximately symmetrical halves, and pivots forming connections between the two halves, one of which pivots contains a concentric aperture. 70

3. A magazine for moving picture machines, comprising a suitably supported casing, containing two telescoping and approximately symmetrical halves, a spindle and pivots forming connections between the halves of the casing, independent of the spindle, one of which pivots contains a concentric aperture through which the spindle 75 may project into the casing. 80

4. In a magazine for moving picture machines, the combination of a standard, containing a supporting arm, a semicylindrical receptacle secured thereto, a semicylindrical cover telescoping the same, and pivots forming connections between the cover and receptacle, one of which pivots contains an aperture concentric with the axis of the pivots. 90

5. In a magazine for moving picture machines, the combination of a standard, containing a supporting arm, a semicylindrical receptacle secured thereto, a semicylindrical cover telescoping the same, a spindle concentrically arranged within said semicylindrical receptacle and cover, and pivots forming connections between the cover and receptacle, one of which pivots contains a concentric aperture, through which the spindle may 95 project into the casing. 100

6. In a magazine for moving picture machines the combination of two telescoping and approximately symmetrical halves, pivots forming connections, one of which pivots contains a concentric aperture, a standard 105 containing a journal bearing which extends through said aperture in the pivot and into said telescoping halves, and a spindle journaled in said bearing. 110

7. In a magazine for moving picture machines, the combination of a cylindrical casing containing two halves, one of which swings upon and telescopes within the other, and each of which contains an axial opening in one of its side walls, pivots forming connections between said halves, one of which pivots contains a concentric aperture, a standard supporting said casing and containing a journal bearing projecting 115 through said openings in the two halves of the casing and the aperture in the pivot, and a spindle, journaled in said bearing. 120

8. In a magazine for moving picture machines the combination of a cylindrical 125 casing containing two telescoping semicylindrical halves, reinforcing washers secured thereto, rivets pivotally connecting said halves together, one of said rivets being hollow, and a suitably supported spindle 130

extending through said hollow rivet and into said casing.

9. In a magazine for moving picture machines the combination of a standard, two spindles journaled therein, a crank upon one of the spindles, pulleys upon said spindles, a belt connecting said pulleys, a semicylindrical receptacle secured upon standard and a semicylindrical cover telescoping the receptacle, one of the walls of the receptacle and cover containing a perforation concentric with the casing through which one of the spindles enters the receptacle.

10. In a magazine for moving picture machines, the combination of a semicylindrical receptacle, a semicylindrical cover telescoping the same, a concentrically arranged spindle means for rotating the spindle, and pivots forming connections between the two halves, one of which pivots contains a concentric aperture through which the spindle may project into the casing.

11. In a magazine for moving picture machines, the combination of a cylindrical casing containing two symmetrical halves

pivoted together and one telescoping within the other, a reel, a standard supporting said casing, a spindle journaled in said standard and extending into the casing, and containing a circumferential groove, and a spring latch engaging said groove.

12. In a magazine for moving picture machines, the combination of a cylindrical casing containing two symmetrical halves pivoted together and one telescoping within the other, a reel, a standard supporting said casing, a spindle journaled in said standard and extending into the casing, and containing a circumferential groove, a spring latch engaging said groove, a drive shaft, pulleys upon the spindle and shaft and a belt connecting said pulleys.

In witness whereof I have executed the above application at Chicago, Illinois, this 8th day of March 1907.

JOHN J. PINK.
